DOOR LOCK

Fritz Albert Nilsson, Jonkoping, Sweden

Application May 16, 1938, Serial No. 208,285
In Sweden November 5, 1935

4 Claims. (Cl. 292—140)

This invention relates to door locks of the type having a latch-bolt which is operated by means of handles, when the door is to be opened, and moved into locked position by a spring which is not under tension or is under only a slight tension when the door is open, but is automatically put under a sufficient tension to actuate the bolt immediately before the door in its closing movement reaches its fully closed position.

10 An object of the invention is to provide a door lock of the said type which does not present any projecting parts in the open position of the door and positively prevents operation of the handles as long as the door is open. Another object is to 15 secure a practically noiseless, positive closing of the door.

The invention is characterized, chiefly by the fact that the operation of the said spring to put same under tension at the end of the closing movement of the door is effected by a slide movable at right angles to the face of the door which controls, by means of a rocking lever, a lever supporting the spring which is mounted to swing in a plane parallel to the face of the door.

25 In the accompanying drawings, several embodiments of the invention are illustrated.

Fig. 1 is a side elevation, partly in section, of the lock in locked position.

Fig. 2 is a horizontal section of the lock on the line A—A of Fig. 1.

Fig. 3 is a horizontal section of the lock on the line B—B of Fig. 1.

Fig. 4 is a vertical section on the line C—C of Fig. 1.

Fig. 5 is a side elevation of the lock as mounted in the door.

Fig. 6 is a partly sectional side elevation of the lock, with the handles shown in depressed position to open the door.

Fig. 7 is a partly sectional side elevation of the lock showing the position of the parts of the lock after the door has been removed from the door-post and the handles have been released.

Fig. 8 is a partly sectional side elevation of a somewhat modified construction with the parts shown in locked position.

Fig. 9 is a partly sectional side elevation of still another modified embodiment of the lock.

Fig. 10 is a sectional view on the line D—D of Fig. 9.

Fig. 11 is a partly sectional side view showing the same parts as Fig. 9 with the latch-bolt retracted into the housing of the lock.

Fig. 12 is a partly sectional side elevation of still another embodiment of the lock.

With reference to Figs. 1—7 of the drawings, the numeral 1 indicates the frame of the door, in which the lock is mounted. 2 is the stationary door-post and 3 is the keeper plate having an opening to receive the latch-bolt of the lock. 4 is the housing of the lock mounted in a recess of the door frame, and 5 and 6 are the associated face plates which are secured by screws 7 to the fore edge of the door. The face plate 6 is thinner than the face plate 5 and is situated outside the same, covering it completely. The face plates are connected together by a screw or screws 7¹. The numeral 8 designates the latch-bolt which is movable in and out through an aperture formed in the face plates 5, 6. The bolt is guided by 15 said aperture and also by a square pin 9 on which the bolt rests. Cooperating with the bolt is a rollback 10 mounted on the square spindle 12 of the two handles 11. Inserted between the rollback 10 and the rear wall of the housing 4 is a 20 blade spring 13 adapted to restore the handles to their uppermost, or normal, position as soon as they are released. In this connection the pin 9 acts to limit the movement of the rollback. In the housing, below the latch-bolt, a bell crank 25 lever 14 is mounted to rock about a knife edge 15 secured to the side walls of the housing. One arm of said bell crank lever which is comparatively thin carries intermediately between its ends a square pin 16 around which a spiral 30 spring 17 is coiled. The upper end of this spring bears against a shoulder of the latch-bolt 8 for urging the same outwards. Said upper end of the spring 17 projects beyond the free end of the respective arm of the bell crank lever 14 and 35 bears against a lateral projection 18 thereof. The spring 17 presses against this projection with a slight initial pressure in certain positions of the bell crank lever. With the spring 17 thus bearing against the projection 18, the spring and the 40 bell crank lever form a unitary assembly.

Mounted to reciprocate in a transversely extending slot formed in the inner face plate 5 is a slide 19 guided between the two face plates 5 and 6. This slide is formed with an angularly 45 bent extreme end 20 which in in the closing of the door may be operated by an abutment 21 provided in the keeper plate of the door-post. The face plate 6 carries a pair of angularly shaped projections between which the bent extreme end 50 20 of slide 19 is guided, as shown in Figs. 4 and 5. In the outermost position of slide 19, the end 20 thereof is flush with the front face of the door, so that there are no projecting parts at said edge. The main portion of the slide 19 situated be- 55

tween the face plates 5, 6 is wider than the bent end 20. Due to this fact the outward movement of the slide is limited by the angularly bent projections of face plate 6, Fig. 5. Secured to the face plate 6 is a pivot 22 carrying a rocking lever 23. The end of this rocking lever situated inside the housing 4 of the lock is adapted to actuate the lower arm 24 of the bell crank lever 14 in order to move same downwardly. Immediately above the latch-bolt 8 is a weak coil spring 25 which permanently tends to retract the bolt. This coil spring has for its only purpose to prevent the bolt when in its innermost position from being thrown out, as for instance by the centrifugal force, when the door is moved quickly. The inner end of the latch-bolt 8 is formed with a head 26 against which the fork-shaped upper end of the rollback 10 embracing the latch-bolt bears when the door is opened. When the latch-bolt is in its outermost position, the head 26 cannot touch the rollback but bears against a soft stop 27 of leather or the like. This stop is held in position by an inwardly bent flap 28 cut out in the side wall of the housing.

25 The operation is as follows:

Let it be assumed that the door is in closed position and to be opened. In the closed position of the door all parts of the lock are in the positions shown in Figs. 1-4. The latch-bolt is held in its outermost position, in engagement with the aperture of the keeper plate 3, under the action of spring 17 which is maintained in this position, under a slight tension, by the action of the bell crank lever 14, under the control of the rocking lever 23 pressing on arm 24 of said bell crank lever. The rocking lever 23 in its turn is maintained in its position by the action of the abutment 21 and the bent end 20 of slide 19. The handles 11 are held in their uppermost, horizontal position by the action of spring 13. In order to open the door the handles 11 are depressed. This will cause the rollback 10 to operate the latch-bolt, moving same until it is checked by the upper end of the spring 17 hitting the pin 9. When the latch-bolt commences to move inwards, the lever arm 24 tends to move upwards but will be prevented from doing so by the rocking lever 23, which is held by the end 20 of slide 19. As a result, the spring 17 is put under tension and is moved away from the projection 18 into the position shown in Fig. 6. As soon as the latch-bolt has passed beyond the edge of the keeper plate 3, the door can be opened. When the door, during the opening movement, has been removed from the door-post 2, the pressure exerted by the projection 21 upon the slide 19 ceases, allowing the arm 24 to freely move upwards. In this movement the bell crank lever 14 moves to the right, until its projection 18 again comes into contact with the spring 17. This position is shown in Fig. 7. The elements will now remain in this position as long as the door is open, even after the handles have been released, the release of the handles only resulting in a returning of the rollback to its normal position in engagement with stop 9, without actuating the latch-bolt. While the elements are in this position, the spring 25 positively prevents the latch-bolt from projecting beyond the door edge from one reason or the other. If, for instance, a pressure is unintentionally exerted upon the slide 19, when the door is open, the elements will immediately return to the position shown in Fig. 7.

75 To close the door it is only necessary to push

or pull same. When the door is at a distance of a few millimeters from the abutting edge of the door-post, the end 20 of slide 19 hits the abutment 21 and in the continued movement of the door the slide 19 is shifted from the position shown in Fig. 5 into the position shown in Figs. 3 and 4. This will turn the lever 14 into the position shown in Fig. 6 and put the spring 17 under tension, moving the latch-bolt a little outwards, until its end comes to bear against the keeper plate 3. As soon as the end of the latch-bolt passes beyond the lateral edge of the keeper plate, that is, just as the door hits the abutting edge of the door-post, the spring 17 will urge the latch-bolt out into the opening of the keeper, thereby latching the door. The spring 25 is so weak as not to be of any effect against the influence of spring 17.

Fig. 8 illustrates a modified form of the lock. Instead of using a separate spring (as 25) for maintaining the latch-bolt 8 in its innermost position, I here utilize the rollback controlling spring 13 for this purpose. To this end the bell crank lever 14 is formed with a short additional arm 30 directed substantially oppositely to the arm 24. On said short arm 30 presses a lower extension 31 of spring 13. The latch-bolt is thus held in its innermost position by a weak spring action. This weak spring action is overcome when the arm 24 is depressed in the locking operation so that in this case the entire force of spring 17 will be utilized for moving the latch-bolt outwards into engagement with the door-post. Fig. 8 also shows a retaining device for the door handles 11 with the object in view of preventing a depressing of the handles when the door is open. To this end the bell crank lever 14 is formed with a detent 32 adapted to cooperate with a projection 33 of the rollback. In the locked position shown in Fig. 8, the detent 32 is out of the path of the projection 33. When the latch-bolt is retracted and the door is open the detent 32, however, will engage the projection 33, thereby preventing a depressing of the handles. Said engagement is released at the very instant when the door is closed and the lever arm 24 is depressed.

As will appear from Fig. 2, the latch-bolt is symmetrical as seen in plan view. This will permit the use of the lock both for right-hand and left-hand doors, a shifting from one type of doors to another only requiring a turning over of the face-plate 6 so as to move the slide 19 and the bell crank lever 23 to the opposite side of the door. This change will move the arm 23 to the upper pin 22 shown in Fig. 4.

In the embodiment shown in Figs. 9-11 the latch-bolt 8, the rollback 10 and the rollback actuating spring 13 are arranged substantially in the same way as in the embodiment first described. The latch-bolt is formed with a downwardly opening recess 39 engaged by one arm 40 of a bell-crank lever 40, 41, mounted on a knife-edge 42 the other arm 41 of which cooperates with one end of a U-shaped blade spring 43 which may swing up and down while guided by a strap 44. The upper arm of said spring carries an arm 45 engaged by the lower arm of the spring for limiting the movement of the spring arms from each other. The free end of the lower arm of spring 43 rests upon an upwardly directed end of an angularly shaped element 46 mounted in a projecting part 47 of the housing 4, the downwardly directed point of which bears against a transversely movable slide 48 adapted to co-

operate with a stationary stop attached to the door-post. The other likewise upwardly directed end of the angular element 46 is hook-shaped and suspended on a downwardly and laterally bent flap 47¹, cut out from the top wall of the housing part 47, as shown in Fig. 10. The arm 40 of the bell crank lever 40, 41 engaging the latch-bolt 8 has riveted to it a blade spring 49 bearing against the side of the recess 39 remote from the arm 40 at a point which is situated on a lower level than the contact point between said arm 40 and the opposite side of the recess. The lower edge of the side of the recess 39 engaged by the arm 40 is rounded, as indicated in Fig. 9, to allow the movement of the latch-bolt without interrupting the contact between the arm 40 and the respective side of the recess 39.

The operation of this embodiment is as follows: In the locked position of the door the elements 20 of the lock are in the positions shown in Figs. 9 and 10. When the door is to be opened, the handles are depressed causing the rollback to retract the latch-bolt 8 into the housing 4 against the action of spring 13. In this movement the bell crank lever 40, 41 turns about its knife-edge from the position shown in Fig. 9 to the position shown in Fig. 11. In the said first-mentioned position the spring 49 is pressed against the arm 40 and according as the latch-bolt 8 moves into the 25 housing, the spring 49 is allowed to retire from the arm 40 due to its spring force. In the inward movement of the latch-bolt the spring 49 will therefore be released to a certain extent. In the above said turning of the lever 40, 41 the lever arm 41 depresses the upper arm of spring 43, thereby putting the spring under tension. This is due to the fact that the lower arm of spring 43 is still in engagement with the angular member 46 and cannot move downwards. As soon as 30 the opening of the door commences, the slide 48, however, is allowed to move outwards and as soon as the slide is out of engagement with the stop of the door-post, it has been moved to its extreme outer position by the action of spring 43, inasmuch as the lower arm thereof in its tendency to retire from the upper arm of the spring, until it again comes into contact with the arm 45, turns the angular member 46 downwards. As soon as 35 the handles are released, the spring 13 restores the rollback to its normal position in contact with the stop 9, thereby restoring the handles to their uppermost position. This operation, however, has no influence on the latch-bolt, which is maintained in its innermost position under the action 40 of a certain spring pressure. This is due to the fact that an outward motion of the latch-bolt would require forcing the spring 49 towards the arm 40 and, consequently, said spring will offer a certain resistance to the outward motion of the 45 latch-bolt which is sufficiently high to prevent the latch-bolt from sliding outwards due to shaking or rapid swinging of the door.

The locking of the door is effected without depressing the handles, merely by shutting the 50 door. As soon as the slide 48 hits the stationary stop, not shown, it will be urged into the housing 47, causing the angular member 46 to swing upwards with a consequent upward movement of the lower arm of spring 43, thereby putting this 55 spring under tension. The spring 43, therefore, tends to turn the bell crank lever 40, 41 into the position shown in Fig. 9 but is prevented from doing so until after the door has been closed far enough to allow the latch-bolt to enter the aperture of the keeper plate of the door-post. Simi-

larly as in the embodiment already described, the putting under tension of the spring controlling the forcing out of the latch-bolt is only effected just immediately before the forcing out is to take place.

Fig. 12 shows an embodiment which agrees substantially with that shown in Fig. 8 from which it differentiates essentially by the fact that the spring 13 does not only actuate the rollback 10 and the lever 14 to retain the latch-bolt in retracted position but is also formed as a stop for limiting the outward motion of the latch-bolt. To this end the upper portion 50 of spring 13 is formed with a downwardly bent portion adapted to be engaged by an elastic block 51 mounted in the rear head 26 of the latch-bolt.

When the lock is used in connection with new buildings it may happen that the door or the door-case shrinks so that in the locked position of the door there is an undue wide clearance between the keeper plate of the door-post and the face plate of the door. This may give rise to a snap when the latch-bolt comes into contact with the keeper plate when released as a result of the slide striking the stationary stop of the door-post. In order to avoid this drawback I may provide an adjustable stop to limit the inward movement of the latch-bolt, when the handles are depressed for opening the door. Such an adjustable stop is shown in Fig. 8 in the form of a nut 52 on a screw 53 rotatably mounted in the face plate which is accessible at the front edge of the door. Said stop 52 is adapted to be engaged by an inclined surface 54 of the latch-bolt 8, so that it will be displaced inwards or outwards upon rotation of the screw 53. When due to shrinking, the clearance between the keeper plate and the face plate in the locked position of the door is too wide, the stop nut 52 may be 30 adjusted by turning the screw 53 so that the latch-bolt can only be retracted as much as is necessary to allow the opening of the door.

What I claim is:

1. A door lock comprising, in combination, a 45 housing to be mounted in a door, a latch-bolt, a rollback for actuating said bolt into unlocked position, a spiral spring in constant engagement with said bolt to actuate same into locked position, a lever carrying said spiral spring, said lever being connected with said spring so as to allow the same to be put under tension without operating the lever upon movement of the bolt into unlocked position, a rocking lever to actuate said spring carrying lever, and a slide movable 50 transversely of the plane of the door to control said rocking lever, said slide being released upon the opening of the door so as to allow the spring carrying lever to move under the action of the spring into a position to relieve the spring in 55 order to allow the bolt to remain in its innermost position in the open position of the door.

2. A door lock comprising, in combination, a housing to be mounted in a door, a latch-bolt, a shaft extending transversely of the plane of the 65 door, a rollback on said shaft to move the bolt into unlocked position, handle means to effect operation of the rollback to unlocked position, a spring to actuate the bolt into locked position, a lever carrying said spring, means for controlling 70 said lever to cause it to put the spring under tension at the end of the closing movement of the door, the rollback and said spring carrying lever being formed with projections to engage each other for preventing operation of the rollback 75

and its handle means in the open position of the door.

3. A door lock comprising, in combination, a housing to be mounted in a door, a latch-bolt, a rollback to actuate said bolt into unlocked position, a spring free of tension in the open position of the door to actuate said bolt into locked position, a lever carrying said spring, a rocking lever to actuate said spring carrying lever, a transversely movable slide to actuate said rocking lever to cause it to put the spring under tension due to the slide striking a stationary stop at the end of the closing movement of the door, and adjustable means to limit the inward motion of the bolt 10 when actuated by the rollback.

4. A door lock comprising, in combination, a housing, a latch bolt, a rollback to actuate said bolt into unlocked position, a spring to actuate said bolt into locked position, a lever carrying said spring, said lever having a projection extending into the path of movement of said spring for keeping the spring relieved in the open position of the door, means for operating said lever to bring its projection out of engagement with said spring at the end of the closing movement 10 of the door, and a spring to maintain the latch bolt retracted in the housing of the lock in the open position of the door.

FRITZ ALBERT NILSSON. 15
